Patented Apr. 1, 1919.

UNITED STATES PATENT OFFICE.

OLIVER EARLE CONKLIN, OF BOSTON, AND HERBERT PERCIVAL HOLLNAGEL, OF WEST NEWTON, MASSACHUSETTS.

LIGHT-PROJECTION APPARATUS.

1,299,397.

Specification of Letters Patent.

Patented Apr. 1, 1919.

Application filed May 12, 1917. Serial No. 188,147.

To all whom it may concern:

Be it known that we, OLIVER E. CONKLIN and HERBERT P. HOLLNAGEL, citizens of the United States, respectively, and residents of Boston, in the county of Suffolk, and West Newton, in the county of Middlesex, both in the State of Massachusetts, have invented new and useful Improvements in Light-Projection Apparatus, of which the following is a specification.

This invention relates to the production of a concentrated beam of light and more particularly to an automobile headlight or a military searchlight adapted to produce a flat beam of light whose spread is adapted to illuminate any desired horizontal arc in a given plane without projecting much if any light obliquely to the plane, this application being in the nature of an improvement on our prior application Sr. No. 129,001, filed November 1, 1916.

The principal objects of the invention are to project a concentrated beam of light horizontally without wasting light upwardly or downwardly, thereby to obtain a more perfect control of the beam, to provide improved projecting apparatus having a focal region of at least one substantial dimension whereby a relatively large light source may be employed and still be maintained in the focus of the reflector so as to produce a concentrated beam of light. Another object of the invention is to produce a beam of light of such angular extent in the horizontal direction as to avoid the necessity of sweeping the searchlight over the horizon in order to illuminate a considerable area, as for example, in illuminating a broad expanse of water. Still another object of the invention is to provide projection apparatus of such character that an incandescent lamp can be used for producing high power beams, thus avoiding the necessity of using arc lamps for the purpose.

Other objects of the invention will be apparent from the following description and the accompanying drawings, which are largely diagrammatic, in which,—

Figure 1 is a vertical longitudinal central section of one embodiment of the invention;

Fig. 2 is a horizontal longitudinal central section of the same embodiment, taken on line 2—2 of Fig. 1;

Fig. 3 is a vertical longitudinal central section of another embodiment of the invention;

Fig. 4 is a horizontal longitudinal central section of the second embodiment taken on line 4—4 of Fig. 3;

Fig. 5 is a diagram in perspective illustrating the operation of the apparatus;

Fig. 6 is a diagram in side elevation corresponding to Fig. 5;

Fig. 7 is a view in horizontal central section of the diagrams in Figs. 5 and 6;

Fig. 8 is a view similar to that of Fig. 7, showing the conjoint use of reflecting and refracting light deflecting means in combination with a cylindrical reflector; and

Fig. 9 is a horizontal section of a modified form of refracting means.

The present invention involves apparatus for producing a beam of light, the vertical spread of which is made sufficiently small to avoid the useless projection of light above and below the horizontal plane, and which is therefore adapted to increase the concentration of light along the horizontal. By virtue of the peculiar construction of the apparatus the lateral spread of the beam can be determined independently of the vertical spread. This peculiar construction consists primarily in the use of separate means for controlling the lateral and vertical spread of the beam, and in the embodiment of the invention shown in Figs. 1 and 2 this construction is as follows:

A main reflector M having a substantially cylindrical contour, that is, a contour generated by the movement of a substantially straight line remaining parallel to itself and constantly intersecting a curve, is disposed, for the preferred uses of the invention, with its axial plane substantially horizontal. For most purposes the cylindrical reflector is given a parabolic contour as shown in Fig. 1, although it is to be understood that other contours such as the elliptical or hyperboloidal or other contour may be employed instead of the parabolic. The parabolic reflector M, instead of having a point focus as the ordinary paraboloidal reflector, has a line focus as indicated at FF in Figs. 1 and 2. A lamp bulb B having a rectilinear light source L is preferably employed with the light source disposed along

the axis of the reflector M in the central region of the focal region FF. The cylindrical bulb B may be mounted in any convenient manner, but for the purpose of illustration we have shown it mounted in openings 1 in the end walls E of the reflectors, gaskets or washers 2 preferably being provided between the lamp bulb and the annular edges of the end walls E surrounding the lamp bulb.

For a purpose hereinafter described, the end walls E are preferably made reflecting on their inner surfaces and they are preferably given a contour similar to that of the main reflector M, that is, a parabolic cylindrical contour. And in the preferred construction of the apparatus shown in Figs. 1 and 2, the focal line of the parabolic end walls E is disposed substantially coincident with the directrix D of the central element of the main parabolic reflector M, it being understood that the directrix D is disposed in the rear of the reflector a distance equal to the focal length of the reflector and in perpendicular relationship to the horizontal axial plane of the reflector. If the end walls E were continued around the rear of the main reflector M they would be disposed along the dash line E' shown in Fig. 2 and would meet in the rear of the directrix D of the main reflector M, as indicated.

The embodiment of the invention shown in Figs. 3 and 4 is similar to that shown in Fig. 1, but instead of having parabolic end walls E the end walls may be given any suitable contour, flat end walls as shown at E₁ being suitable. Over the front of the parabolic cylindrical reflector R is placed a lens C which is cylindrical and which has its line focus disposed at the rear of the reflector R, and preferably substantially coincident with the directrix D₁ of the reflector R. As shown in Figs. 3 and 4, the spherical lamp bulb B₁ may be employed instead of a cylindrical lamp bulb as in Figs. 1 and 2, and it is to be understood that either type of bulb may be employed in either embodiment of the invention. As in Figs. 1 and 2, the light source L₁ in Figs. 3 and 4 is preferably rectilinear and preferably disposed along the line focus F₁ of the reflector R.

The operation of both types of the improved apparatus will be more clear by reference to the diagrams in Figs. 5 to 7. In these diagrams a parabolic cylindrical reflector P is shown in outline, this reflector corresponding to the main reflectors M and R in Figs. 1 to 4. The parabolic reflector P has a line focus F₂ and its vertical longitudinal central section has a directrix D₂. A ray of light a emanating from the central point 3 of the line focus F₂ and striking the reflector P at 4 will be reflected horizontally as shown in Fig. 6, but in a horizontal

direction oblique to the central vertical plane of the reflector which contains the point 3 and the directrix D₂, the particular parabolic element of the reflector P which contains the point 4 being indicated at 5 in Figs. 5 and 7. A ray b emanating from the central point 3 of the line focus F₂ and striking the lower portion of the reflector at point 6 in parabolic element 25 will be reflected horizontally, as shown in Fig. 6, and obliquely to the vertical central plane of the reflector as shown in Fig. 7. As shown in Figs. 5 to 7, each of the reflected rays of light which radiate from point 3 to the reflector, illustrated for example by rays a and b, are reflected by reflector P as if coming from the directrix D₂. Thus, if lines be extended rearwardly in the direction of the reflected rays they will intersect the directrix. In Figs. 5 and 6 for example, the reflected rays a and b if continued rearwardly would intersect the directrix D₂ at points a' and b' respectively. This is true of all rays emanating from the central point of the line focus F₂ and forms the basis of the present invention.

By disposing parabolic end reflecting walls as shown in Figs. 1 and 2 all rays of light such as rays r, s, t, u and v, which emanate from the central point of the line focus F and which are reflected from the main reflector M to the end walls E, will be projected in parallelism to the axis of the reflector, this resulting from the fact that the main reflector M renders the rays parallel to the horizontal axial plane of the apparatus and the end walls E render the rays parallel to the vertical axial plane of the apparatus. This is due to the fact that, as described in connection with Figs. 5 to 7, all such rays are reflected from the main reflector as if coming from the directrix D of the main reflector, and inasmuch as the line focus of the end walls E is coincident with the directrix, rays directed from the directrix are likewise directed from the focus of the end walls and will therefore be rendered parallel to the axial plane containing the directrix D. A ray t, for example, striking the main reflector M at 7 will be reflected as if coming from the point 8 in the directrix D to the end reflector E at point 9, the ray thence being projected in parallel relationship to the axis 10 of the reflector. Likewise the rays u and v striking the main reflector at points 11 and 12 respectively will be reflected to the points 13 and 14 of the end walls along paths which if extended rearwardly will intersect the directrix at points 15 and 16, and thence be projected in parallelism with the axis 10. Fig. 2 only shows rays striking the lower half of the reflector, but rays striking the upper half of the reflector, such as rays r

and s in Fig. 1, would be projected in like manner.

In the embodiment of the invention shown in Figs. 3 and 4 similar results are obtained but in a slightly different manner. In this embodiment all rays of light emanating from the central point 17 of the light source and striking the reflector R will, as above explained, be reflected as if coming from the 5 directrix D_1 , a virtual image of the light source being formed along the directrix. Inasmuch as the focus of the cylindrical lens C is coincident with the directrix D_1 , the rays reflected from reflector R, which appear to come from the virtual image of the 10 light source at the focus of the cylindrical lens are rendered parallel to the vertical axial plane of the apparatus. The reflector R renders the rays parallel to the horizontal 15 axial plane as above described, and consequently the rays are rendered parallel to the axis 20 of the apparatus. To make this clear, rays o and p have been shown as emanating from the central point 17 to the 20 points 21 and 22 of the reflector R, the rays thence being reflected along lines intersecting the directrix at points 23 and 24 to the cylindrical lens C, where they are rendered 25 parallel to the axis 20. Rays such as m and n striking the upper half of the reflector 30 would be reflected in like manner as if coming from points 25 and 26 in the directrix D_1 . When employing the cylindrical lens C the end walls E_1 may be either light reflecting, light diffusing or light absorbing, 35 but they are preferably so constructed as to diffuse the light incident thereto, the diffused light passing outwardly through the cylindrical lens so as to illuminate objects 40 outside of the main beam of light relatively feebly.

From the above description it will be apparent that the essential characteristics of the present invention involve two optical 45 means, one of which renders the rays substantially parallel to a horizontal plane and the other of which renders the rays substantially parallel to a vertical plane. Another characteristic feature involves the use of optical 50 means, one or more of which have line foci, one of the foci being disposed in the region of the virtual focus of the other means. While these characteristics may be utilized in any one of a number of embodiments, two of the embodiments being shown 55 by way of example, the most satisfactory means for most purposes is that shown in Figs. 3 and 4. It will be understood that the width of the apparatus may be varied 60 suitably to determine the proportionate amounts of light reflected from the end walls and passing directly through the opening in the forward end of the apparatus respectively. In the embodiment in Figs. 1 and 65 2, for example, by making the width rela-

tively small the ratio of light incident directly to the end walls to the amount of light first striking the main reflector can be increased, and vice versa. In the embodiment shown in Figs. 3 and 4 the ratio of the 70 light reflected directly through the lens C to the diffused light from the end walls E_1 may be increased by increasing the width of the main reflector and cylindrical lens.

It will also be understood that a certain 75 amount of lateral flare will result when employing a light source extending along the line focus of the main reflector on either side of the central point of the line focus, and by varying the length of the light source 80 the lateral spread of the beam may be controlled. By increasing the length of the light source the spread is increased, and by decreasing the length of the light source the spread is decreased. When the light source 85 is disposed substantially wholly in the central point of the line focus the projected beam comprises rays substantially all of which are parallel. So long as the light source is confined substantially to the line 90 focus of the main reflector substantially no light is reflected upwardly or downwardly, a fan-shaped beam being produced on the contrary, the lateral spread of which can be controlled as above described. When employing 95 apparatus for automobile headlighting where it is desirable to prevent light being projected upwardly but to project some light downwardly to the nearer and intermediate portions of the roadway any 100 well-known means may be employed to direct a portion of the light downwardly. For example, either the upper or lower half of the reflector may be given a different contour or a different position with respect to 105 the light source than the other half.

While the use of parabolic end walls and a cylindrical lens have been described separately, it is to be understood that they may be employed conjointly if desired, and indeed the best results are obtained by using the two features conjointly. This may be done, for example, as shown in Fig. 8, wherein a main reflector 31 is provided with parabolic end walls 32 and 33 having their 110 foci coincident with the directrix 34 of the central parabolic element of the parabolic cylindrical reflector 31. A cylindrical lens 36 is positioned in front of the main reflector 31 in the same manner as described 115 in connection with Figs. 3 and 4 except that the lens only extends across the central portion of the front of the reflector, leaving spaces 37 and 38 on either side of the lens between the lens and the end walls 32 and 120 33. With this arrangement all rays of light issuing from the central point 39 of the focus of the main reflector 31 which are reflected from the main reflector 31 directly to the 125 cylindrical lens, as are rays 41 and 42, will 130

be rendered parallel to the vertical central plane of the reflector, as above described. Those rays, such as rays 43 and 44 which are reflected from the main reflector 31 to 5 the end walls 32 and 33, will pass out through the openings 37 and 38 in the same direction as the rays 41 and 42, that is, in a direction parallel to the vertical central plane of the main reflector 31, which plane 10 contains the directrix 34, it being understood that all of these rays are rendered parallel to the central horizontal plane containing the axis of the main reflector 31 by the main reflector 31. With the combined 15 arrangement shown in Fig. 8 both the rays which are reflected from the main reflector to the end reflectors and those rays which are reflected by the main reflector through the cylindrical reflector 36 are rendered 20 parallel to the vertical central plane. It will of course be understood that when using a light source extending laterally somewhat away from the central point 39 or when displacing the focus of the cylindrical lens or 25 the parabolic end walls somewhat from the directrix 34 all of this light will not be rendered precisely parallel to the central vertical plane, but the tendency will be to deflect all of the rays toward the central vertical plane so as to concentrate the central 30 portion of the beam.

It will be apparent that some light will be reflected from the main reflector 31, in Fig. 8, so as to pass through the openings 35 37 and 38 without striking either the end reflectors or the cylindrical lens. All such light will flare outwardly and will result in spots of light displaced laterally in both directions from the main central beam. If 40 this is found to be undesirable for the purpose for which the apparatus is intended to be employed, the cylindrical lens may be modified as shown in Fig. 9. In this construction the lens 51 is cylindrical throughout 45 out the central portion, that is, throughout the portion between the lines 52 and 53, the line focus of this portion preferably being disposed in the directrix of the central parabolic element of the main reflector. On 50 either side of the central portion 51 are portions 54 and 55, these portions being of such width as to close the spaces 37 and 38 shown in Fig. 8. Thus, when employing the cylindrical lens of Fig. 9 with the structure 55 shown in Fig. 2 the lens would be disposed over the forward opening of the reflector ME in the position obtained by moving the lens of Fig. 9 directly to the left to the plane of the forward edge of the reflector M and 60 end walls E, in which position the line focus of the central portion 51 would be coincident with the directrix D of Fig. 2. With the construction shown in Fig. 9 the light which would otherwise pass through the spaces 37 65 and 38 (Fig. 8) passes through the negative.

lens portions 54 and 55 and is deflected inwardly by the negative lens. Thus, the beams of light which pass through the negative portions 54 and 55 are diffused and spread out laterally, and by suitably shaping the negative portions this beam can be made to extend inwardly substantially to the main central beam so that no gaps will appear on each side of the main central beam between the central beam and the 70 beams passing through the spaces between the central cylindrical portion 51 and the end reflectors. It is true that the negative portions 54 and 55 will also deflect the parallel rays passing therethrough from the end 75 reflector, such as rays *u*, *v*, and *t*, in Fig. 2, but these rays pass almost directly through the negative portions so as to be little affected and moreover, the portions of these two beams of light which are deflected inwardly will pass through the main central beam and assist in illuminating the regions on either side of the main beam so as to produce a gradual decrease in the intensity of the beam from the center outwardly. The 80 lateral spread of the beam may be varied by increasing or diminishing the power of the cylindrical lens or by changing the position of the foci of the end reflectors E. The lateral spread is least when the foci 85 of the lens and end reflectors coincide with the directrix of the reflector, and by shifting the foci forwardly or rearwardly central concentration can be diminished, the lateral 90 spread thereby being increased.

It is to be understood that such terms as horizontal, vertical, upward, downward, etc., are herein employed merely in a relative sense for convenience in referring to relative positions and directions and that they are not employed in the absolute sense with respect to the earth's surface, although in the preferred use of our apparatus they are also accurate with reference to the 100 earth's surface.

We claim:

1. Light projection apparatus comprising a substantially parabolic cylindrical reflector, and light deflecting means having a focus substantially in the directrix of the 115 central parabolic element of the reflector for redirecting a portion of the light reflected from the cylindrical reflector.

2. Light projection apparatus comprising a substantially parabolic cylindrical reflector, and light deflecting means having a line focus substantially coincident with the directrix of the central parabolic element of the reflector for concentrating the projected light in the region of the plane of said central element and directrix.

3. Light projection apparatus comprising a substantially parabolic cylindrical reflector, and a lens having a focus substantially in the directrix of the central parabolic ele- 130

ment of the reflector for redirecting a portion of the light reflected from the cylindrical reflector.

4. Light projection apparatus comprising a substantially parabolic cylindrical reflector, and a lens having a line focus substantially coincident with the directrix of the central parabolic element of the reflector for concentrating the light reflected from the reflector along the central plane containing said element and directrix.

5. Light projection apparatus comprising a substantially parabolic cylindrical reflector, light diffusing end walls for the reflector, and a cylindrical lens disposed in front of the cylindrical reflector with its focus substantially in the directrix of the central parabolic element of the reflector so as to redirect a portion of the light reflected from the cylindrical reflector at least into approximate parallelism with the central plane containing said element and directrix.

6. Light projection apparatus comprising a cylindrical reflector and light deflecting means for redirecting a portion of the light reflected from the cylindrical reflector, the light deflecting means having a line focus disposed at the rear of the reflector in a plane substantially perpendicular to the axis of the cylindrical reflector.

7. Light projection apparatus comprising a substantially parabolic cylindrical reflector and a cylindrical lens disposed in front of the reflector with its focus disposed at the rear of the reflector in a plane substantially perpendicular to the axis of the cylindrical reflector.

8. Light projection apparatus comprising a substantially cylindrical reflector and end reflecting members, the vertical elements of

the end reflecting members being substantially straight and the horizontal elements of the end members being conic sections.

9. Light projection apparatus comprising a substantially parabolic cylindrical reflector, the straight elements of which are disposed horizontally for controlling the vertical spread of the beam, and refracting means having straight vertical elements, said refracting means being designed to control the horizontal spread.

10. Light projection apparatus comprising a substantially parabolic cylindrical reflector, and refracting means having straight vertical elements, and horizontal elements whose thickness diminishes from the center toward the sides.

11. Light projection apparatus comprising a cylindrical reflector having a horizontal focal region, end reflectors for the cylindrical reflector, the end reflectors having foci at the rear of the main reflector, and refracting means forwardly of said focal region for controlling the horizontal spread of the projected beam.

12. Light projection apparatus comprising a cylindrical reflector having a horizontal focal region, end reflectors disposed to deflect a portion of the light reflected from the cylindrical reflector in such manner as to control the horizontal spread of the beam, and refracting means for refracting another portion of the light reflected from the cylindrical reflector so as also to control the horizontal spread of the beam.

Signed by us at Boston, Massachusetts, this 8th day of May, 1917.
